PHOTOELECTRIC EYE UNIT

James M. Gerdom, Overland Park, Kans., assignor to
Honan Sales Company, Inc., Kansas City, Mo.

Filed Sept. 18, 1972, Ser. No. 289,977

Term of patent 7 years

Int. Cl. D13—99

U.S. Cl. D26—1 F

FIG. 1 is a perspective view of a photoelectric eye unit showing my new design;

FIG. 2 is a rear elevational view thereof on a reduced scale;

FIG. 3 is a side elevational view thereof on a reduced scale, the opposite side being a mirror image of the side shown herein;

FIG. 4 is a perspective view of a photoelectric eye unit showing a second embodiment of my new design;

FIG. 5 is a side elevational view, on a reduced scale, of the embodiment shown in FIG. 4, the opposite side being a mirror image of the side shown herein; and

FIG. 6 is a rear elevational view on a reduced scale of the embodiment shown in FIG. 4.

I claim:

The ornamental design for a photoelectric eye unit, substantially as shown and described.
